UNITED STATES PATENT OFFICE.

GEORGE W. NELSON, OF CLEVELAND, OHIO, ASSIGNOR TO THE STEWART MACHINE COMPANY, OF ELYRIA, OHIO, A CORPORATION OF OHIO; ARTHUR J. CURREN TRUSTEE OF SAID THE STEWART MACHINE COMPANY, DEFUNCT.

VENDING MACHINE.

Application filed June 23, 1926. Serial No. 119,020.

My invention relates to vending machines and more particularly to that class of such machines which are adapted to be placed upon street corners, in hotels, railway stations, or other public places for mechanically vending newspapers, magazines or other periodicals.

An object of my invention is to provide a vending machine which will be simple and inexpensive in construction, and simple and positive in its functions of vending the articles placed therein.

Another object of my invention is to provide a machine of this class with means to compensate for variation in the size of the articles to be vended, so that perfection in operation will take place to deliver all the articles placed in the magazine of the machine.

Another object of my invention is to notify a prospective purchaser when there are articles in the magazine of the machine to be vended, and to warn the purchaser whenever the magazine of the vending machine has no articles remaining therein to be vended.

Another object of my invention is to provide an improved vending machine, from the magazine of which, the articles can not be removed unless the proper number of the proper kind of coins are inserted therein, or unless an authorized person unlocks the vending machine so as to enable him to replenish the exhausted supply of articles, and to remove the coins inserted therein.

Another object of my invention is to provide a vending machine which will not permit an article to be withdrawn therefrom until the coin which is inserted has finally reached a receptacle provided for the same.

Another object of my invention is to provide a machine of the class stated which is durable in construction, inexpensive to manufacture, and which is substantially theftproof.

Another object of my invention is to provide a vending machine with means to prevent such rapid return of the mechanism to normal position which would create undue noise, effect undue wear and tear upon the parts of the machine.

The above and other objects of my invention will be apparent from the following de-

scription and drawings wherein one embodiment of my invention is illustrated.

Fig. 1 shows a front elevation of my vending machine;

Fig. 2 shows a side elevation of the same;

Fig. 3 shows a similar view to Fig. 2 showing the closure partly in open position;

Fig. 4 shows a fragmentary side elevation with the closure open to the limit;

Fig. 5 shows a vertical section on the line C—C of Fig. 1 looking in the direction of the arrows;

Fig. 6 shows a vertical section on the line A—A of Fig. 1 looking in the direction of the arrows;

Fig. 7 shows a transverse section on the line B—B of Fig. 6 looking in the direction of the arrows; and

Fig. 8 shows a perspective view of the article shelf.

Referring more particularly to the drawings I have provided preferably, a sheet metal rectangular container 1 held together in any suitable manner by rivets and screws 17, and having the front wall 100 of the container extending upward and cut away at 101 adjacent to the hinges 2 for each access to the interior of the container when a closure 3 is in the position shown in Figs. 1 and 2. The said walls of the container 1 are bent around at each side of the opening to form flanges which extend a short distance across the space above where the hinges 2 are secured to the front wall. Hinged at 2, to the container 1, is a closure 3 preferably made of sheet metal and adapted to cover the cut away portion of the front wall above the hinges, and the top of the container. The front wall of the closure is provided with an opening 4 forming a window therein, and having preferably a pane of glass 5 secured in the same in any suitable manner, whereby the prospective purchaser is enabled to know at a glance whether there remains any article in the vending machine to be sold.

The rear wall 71 of the container 1 is provided with fastening means adapted to be secured to a supporting stand of any suitable type located in a convenient public place.

The container 1 is locked in any suitable manner, preferably by means of a lock bolt 105 and keeper plate generally shown at 102,

carried by the closure which engages a keeper plate secured to the rear wall 71 of the container.

The hinged closure 3 carries a pair of 5 lugs 8, adjacent the hinges 2, and connected to a pair of arms 9 provided with slots 10 to limit the downward swing of the closure 3, on its hinges. The inner ends of the arms 10 are secured in a manner which will 10 be described more fully in another part of this specification. The top of the closure 3 extends beyond the rear wall 71 of the container and downwardly to form a flange 11 which extends over the rear wall of the 15 container 1 to prevent rain or the like from entering the rear of the container. The closure 3 is triangular shaped and composed of sheet metal parts which are secured together by rivets or in any other suitable 20 manner.

The vending machine is capable of being operated by any predetermined number or kinds of coins. Coin slot 6 is provided in the side of the container 1 and the closure 25 3 is provided with a coin slot 7 which registers with the coin slot 6 in the container 1 when the closure 3 is in closed position.

One of the flanges 28, heretofore referred to, adjacent the coin controlled mechanism 30 is cut away at 90 to permit the coin controlled mechanism to be adjusted for various kinds and numbers of coins, when the closure is swung into the position illustrated in Fig. 3 of the drawings.

35 A signal is provided to indicate when all the articles are exhausted from the machine, and this indicating means will be more fully described in the specification following.

Pivoted at 12 on the right hand side of 40 the container 1 is an operating handle 13. Suitable guide members 14 are disposed adjacent to the outer end of the handle 13 and adapted to guide the handle 13 on its pivot to limit the upward and downward movement of the same by means of a pair of stops 45 15 and 15'. The outer end of the handle 13 is bent at substantially right angles upon itself to form a finger gripping portion 16, adjacent the coin slots 6 and 7.

50 It will be seen that when a coin is inserted into the slot 6, and pressure is applied to the handle in a downward direction by the purchaser gripping portion 16 of the handle, the handle 13 will swing on its pivot 12, the 55 complete downward swing of the handle will vend an article at the opening 86 at the bottom of the container 1, adjacent the cut-away portion 87 of the front wall, which will be more fully described in the succeeding 60 portions of this specification.

Disposed on the inside of the container 1, (Fig. 6) on a pivot eccentric to the pivot of the handle 13 and preferably substantially parallel thereto is the normally locked coin 65 controlled operating lever 19 provided with

a link 20 pivoted to its end at 21. The link 20 is detachably fastened by means of a latch 25 to a pin 22 carried by the coin control mechanism 23 is assembled in its channel frame 70 24 and comprising an entire unit held in detachable engagement on the inner side of the right hand wall of the container adjacent the coin slot 6 to enable the coin control mechanism to be removed by an authorized 75 person having access to the interior of the container when such removal is necessary. The lower end of the channel frame 21 of the coin control mechanism rests upon a step pin 26 and is guided into operative position by the guide lugs 27 and retained in this position by engaging a lug 29 carried by the flange 28 of the container. A coin channel 91 is disposed in alignment with the coin chute 85. The coin control mechanism 80 may now be secured in operative position in any suitable manner, preferably by means of lugs 27 and 27' and cut out portions in the channel frame 24.

The above referred to coin control mechanism is described in detail embodied in my co-pending application covering the coin control mechanism, filed concurrently with this application.

The coin controlled operating lever 19 is 95 returned to normal locked position against the stop pin 30 by preferably a coil spring 31 which is provided with securing means at 32, to the side wall of the container. The spring is hooked at its lower end to the lever 100 19 adjacent the outer end thereof. To prevent the spring 31 from returning the lever 19 and snapping it against the limit stop pin 30, thereby causing unnecessary noise and possible damage to the machine, a dash pot 105 33 is preferably provided.

The cylindrical portion 34 of the dash pot 33 is pivoted at one end to the upper portion of the container at 35. The cylindrical portion 34 has formed therein a restricted opening 110 18 and is adapted to receive a piston 36 pivoted to the coin controlled lever 19 and secured thereto by a latch 38 carried by the coin controlled lever 19 to prevent accidental detachment of the same. This piston, however, may be detached from connection with the coin controlled lever 19 when desired.

Adjacent to the pivot end of the coin controlled lever 19 is a headed pin 39 adapted to slidably retain the link 40, operating in 115 its slot 41. The lower extremity of the lower link 40 is pivoted to one of the article delivery levers 42 at 43. There are provided a pair of the article delivery levers 42 at each side of the container, one end of the 120 lever 42 is secured to a shaft 44 journaled in the side wall of the container. The opposite end of the levers 42 engage a vertically disposed link 45 which supports a carriage 46 carrying preferably a series of downwardly 125 60

pivoted prongs 47 in their sockets 48, which engage the article to be vended. The carriage 46 is forced inwardly by the action of a resilient plate 89, and is adapted to slide up and down in trackways formed by flanged members 49 secured to the lower side walls of the container 1 the flanges formed being parallel to the front wall of the container. The inner surface of the container 1 forms 10 the opposite portion of the trackway.

Adjustably carried over a pivot 50, adjacent to the bottom wall 51 of the container 1, is arranged the articles supporting shelf 52. The shelf 52 carries depending lugs 53 15 provided with pins 54 which engage the forked portions of the bifurcated levers 55 keyed to the shaft 50. The article supporting shelf 52 is inclined downwardly towards the front end of the container and provided 20 with depending flanges 56 and 57. The flanges 57 (Fig. 8) have a series of downwardly extending slits 91 cut therein in alignment with and below the normal position of the prongs 47, to enable the prongs 25 47 to partially penetrate the article when the carriage 46 is depressed and to provide for the free return of the carriage and prongs in the upward travel of the same. The forward flange also forms a portion of the 30 trackway, in connection with the flanges 49 in alignment with them, to guide the carriage 46 in its downward travel when delivering an article. Preferably four slotted pins 58, are secured in the side walls of the 35 container, the rear pairs of pins arranged above the forward pair, and all are adapted to receive the ends of the shelf 52 in the slots, to guide the shelf 52 in its horizontal shifting movement. The shelf 52 is shifted by 40 the action of an adjusting lever 59 (Fig. 5) keyed to the same shaft with the bifurcated levers 55. The upper end of the adjusting lever 59 terminates in a pointed spring finger 60, preferably riveted thereto and provided 45 with a handle 61 which extends through the finger portion 60 and terminates in a pointed lug which is adapted to snap into any one of the series of arcuately arranged depressions 62 in the left hand side wall of the 50 container, by the spring action of the pointed finger 60 of the adjusting lever 59. Secured adjacent and substantially parallel to the depression 62 is segmental bar 63 provided with suitable graduations 64 on its side, fac- 55 ing the pointed spring finger 60 of the adjusting lever 59. In this manner the shelf 52 may be tilted to the desired angle depending upon the thickness of the article to be vended, by shifting the pointer 60 along the segment 63, to render more efficient operation of the article feeding mechanism.

The levers 42 are returned to normal position raising the carriage 46 to the position shown in Fig. 6 of the drawing, by the action 60 of the coil spring 65 which is secured to the

inner wall of the container at its upper end, and connected to one of the levers 42 at its lower end, through a wire link 66 fastened to one of the levers 42 substantially at the center thereof, adjacent the link 40 and parallel thereto. To prevent the wire link 66 from striking the link 40, due to the angular relation of the lever 19 to 42, when the handle 13 is depressed, a small coil spring 67 is provided and hooked to the coil spring 65 70 at 68, and secured at its lower end to a slot 69 in the lever 19, and disposed at such an angle to cause the wire link 66 to be pulled away from the link 40, when the levers 19 and 42 are forced downwardly by the handle 13.

Arranged substantially parallel to the shelf 52 are a pair of rods 70 extending downwardly from the rear wall 71 of the container and supported at their forward 85 ends by the flanges 49. Slidably mounted on the rods 70 is a bar 72 having its ends turned upwardly to form flanges thereon provided with pins 73 to engage the slots 74 in the vertical levers 75. The forward side of the 90 bar 72 is bent downwardly to the upper portion of the trackway for the carriage 46. Disposed on the forward side of the bar 72, secured to the flange 88, is the follower plate 76 which is adapted to push the articles to 95 be vended in a forward direction at all times by the action of the springs 77 on the follower levers 75. The follower levers 75 are pivoted at 78 to the side walls of the 100 container 1 and are provided with a series of openings 79 arranged one above the other, and above the pivot 78, to receive one end of the springs in any one of the tension adjusting positions desired. The rear end of the coil springs are secured at 80 to the rear 105 walls 71 of the container. Accordingly the tension of the springs 77 always exerts a pull which swings the follower lever 75 on its pivot 78 to continually force the bar 72 and its follower 76 forwardly against the rear-most article so that the article to be vended is next engaged by the prongs 47 in the carriage 46.

Riveted to the upper end of the follower levers 75 are headed lugs 81 which are adapted 115 to slidably retain the arms 9 by the slots 82 provided therein, in any one of the adjusted positions of the levers 9, heretofore referred to.

Disposed substantially parallel to the rods 120 70 and located above the same, are a pair of similar rods 83 secured at each of their ends in the front and rear walls of the container and adapted to support a coin collecting receptacle 84, in the forward part of the 125 container and adjacent to the coin chute 85 which delivers the coins into the receptacle from the coin control mechanism 23. The pairs of rods 70 and 83 also form additional reinforcement for the walls of the container. 130

Having now described the various parts of my vending machine the operation of which will now be described:

- Assuming the machine and the various parts to be in the position shown in Figs. 1, 2, 5 and 6. A supply of articles are now placed in the container 1 in the following manner. The closure 3 is unlocked and swung downwardly to the limit of its pivot, best shown in Fig. 4 of the drawings, and pulling the arm 9 downwardly. The upper ends of the slots 82 in the arms 9 strike the headed lugs 81 on the upper end of the follower levers 75 which swings the follower lever 75 on the pivots 78, against the tension of the springs 77, sliding the bar 72 to the rear of its travel on the rod 70, carrying with it the follower levers. A series of articles are now placed on the shelf 52 and the spring finger 60 of the adjusting lever 59 is moved along the segment 63 to tilt the shelf 52 a predetermined degree, depending upon the thickness of the articles to be vended.
- The closure 3 is now swung back and locked to the container 1. When an article is desired by a purchaser he inserts the proper coin or coins through the slots 6, 7 and 92 into the coin control mechanism 23. The handle 13 is now depressed downward against the stop pin 15 and downwardly swings with it the coin controlled lever 19, against the tension of the spring 31 which in turn pulls the arm 20 secured to the coin control mechanism at 22, in a downward direction causing the actuation of the coin control mechanism 23 and permitting complete free actuation of the coin controlled lever 19, and delivering the coin through the chute 85 to the receptacle 84. After the coin control lever 19 has traveled downwardly approximately the length of the slot 41 of the link 40 the lug 39 strikes the link forcing the same downwardly which in sequence starts the article delivering lever 42 in its downward movement against the tension of the spring 65 forcing the carriage 46 downwardly in its trackway through the agency of the link 45. The prongs 47, carried by the carriage, engaging the article to be delivered forces the same through the opening 86 in the bottom of the container. The article is then withdrawn through the opening 86 by the operator gripping the same, at the cut-out portion 87 in the front wall of the container.

The return action of the handle 13 and levers 19 and 42 is automatic by the action of the springs 31 and 65. As heretofore stated the return to normal position of the machine is rendered noiseless through the action of the dash pot 34 which dampens the return of the levers by the piston 36 sliding into the cylinder and forcing the air through the restricted opening 18. The machine is thus

noiselessly returned to normal position illustrated in Figs. 1, 2, 5, 6 and 7 of the drawing with no snapping action resulting in damage to the machine.

When it is desired to merely remove the coins from the receptacle 84 the closure 3 is unlocked and swung into position shown in Fig. 3. The slots 82 in the arms 9 travel a distance where they engage the lugs 81 on follower levers 75 and will rest in that position, additional pressure on the closure 3 being necessary to swing the follower levers on their pivots again at the tension of the springs 77.

When the articles in the container are exhausted the follower 76 takes the position to the rear of the window 5 and has printed thereon the words "Sold out" or similar words to indicate that there remain no articles in the apparatus to be vended.

While I have shown and described certain features as constituting my invention it will be understood that parts have been shown for purposes of illustration only, and that I do not desire to be limited to such details, as obvious modifications will occur to a person skilled in the art.

Having thus fully described my invention, what I claim as new and desire to secure by Letters Patent, is:—

1. In a vending machine adapted to vend flat articles, the combination with an article-holding magazine, a slot for the egress of the vended articles disposed in a bottom wall of the magazine adjacent an edge thereof, means to exert a constant pressure against the articles to be vended to press them to that side of the magazine whereby a lower edge of the most forwardly disposed one of said articles will be positioned above and adjacent the said slot, and delivery mechanism for frictionally engaging the forward face of the most forwardly disposed article adapted to be reciprocated in a substantially vertical plane from the exterior of the magazine when it is desired to vend such article, said pressure means comprising a pressure plate, parallel guides for the pressure plate disposed near the bottom of the magazine laterally of the plate and substantially parallel to the bottom wall of the compartment, a cover for the magazine, and means operative responsive to the opening movement of the cover to move the plate from a more forward position to fully retracted position.

2. In a vending machine for vending printed publications, the combination with a sheet metal casing, said casing comprising a hinged cover, mechanism adapted to vertically displace the most forward one of the publications to be vended through a longitudinal slot in the bottom wall of the casing, a pressure plate adapted to be disposed to the rear of a plurality of said publications placed in the casing, parallel guiding

supports for the pressure plate disposed laterally at either side thereof, said plate being journalled on said supports for forward reciprocatory movement, and spring actuated levers disposed laterally of the pressure plate for resiliently applying a forwardly directed effort to the plate adjacent the plate journals.

3. In a vending machine for vending printed publications, the combination with a sheet metal casing, said casing comprising a hinged cover, mechanism adapted to vertically displace the most forward one of the publications to be vended through a longitudinal slot in the bottom wall of the casing, a pressure plate adapted to be disposed to the rear of a plurality of said publications placed in the casing, parallel guiding supports for the pressure plate disposed laterally at either side thereof, said plate being journalled on said supports for forward reciprocatory movement, and spring actuated levers disposed laterally of the pressure plate for resiliently applying a forwardly directed effort to the plate adjacent the plate journals, and means joining the cover and levers adapted when the cover is swung to open position to move the levers in such a direction as to retract the pressure plate for the reception of an additional supply of publications to be vended.

4. In a vending machine for vending printed publications, the combination with a sheet metal casing, said casing comprising a hinged cover, mechanism adapted to vertically displace the most forward one of the publications to be vended through a longitudinal slot in the bottom wall of the casing, a pressure plate adapted to be disposed to the rear of a plurality of said publications placed in the casing, parallel guiding supports for the pressure plate disposed laterally at either side thereof, said plate being

journalled on said supports for forward reciprocatory movement, and spring actuated levers disposed laterally of the pressure plate for resiliently applying a forwardly directed effort to the plate adjacent the plate journals, and means joining the cover and levers adapted when the cover is swung to open position to move the levers in such a direction as to retract the pressure plate for the reception of an additional supply of publications to be vended, the bottom wall of the casing being downwardly inclined towards its front and said guides being disposed substantially parallel to the bottom wall.

5. In a vending machine adapted to vend such articles as newspapers and the like, the combination with a sheet metal casing having a hinged top wall, of an article supporting platform for the casing comprising a forwardly disposed portion adapted to slide forwardly and rearwardly, guides for the said platform supported by the side walls, a rock bar disposed between the platform and the bottom wall and extending transversely of the casing adapted to reciprocate the platform forwardly and rearwardly according to the degree of rotation of said bar, said bottom wall having a transversely extending slot in its forward portion through which articles to be vended may downwardly pass, said platform when moved rearwardly adapted to uncover the slot so as to provide an egress opening for the articles of varying widths according to the degree of rearward movement of the platform, and means to rock the bar a predetermined desired amount according to the thickness of the articles to be vended.

In testimony whereof I hereunto affix my signature this 25th day of June, 1926.

GEORGE W. NELSON.
